UNITED STATES PATENT OFFICE.

AUGUSTUS S. TROWBRIDGE, OF MILFORD, MASSACHUSETTS, ASSIGNOR OF
TWO-THIRDS TO CHARLES W. SHIPPEE, OF SAME PLACE, AND WILLIAM
H. DANIELS, OF BOSTON, MASSACHUSETTS.

ATTACHMENT FOR LASTS.

SPECIFICATION forming part of Letters Patent No. 399,096, dated March 5, 1889.

Application filed September 15, 1888. Serial No. 285,473. (No model.)

To all whom it may concern:

Be it known that I, AUGUSTUS S. TROWBRIDGE, a citizen of the United States, residing at Milford, in the county of Worcester and State of Massachusetts, have invented 5 certain new and useful Improvements in Lining-Supporting Attachments to Forms or Lasts for Shaping the Soles of Boots or Shoes; and I do declare the following to be a full, clear, and 10 exact description of the invention, such as will enable others skilled in the art to which it 15 applies to make and use the same, reference being had to the accompanying drawings, and to the letters and figures of reference marked thereon, which form a part of this specification.

Figure 1 denotes a top view, and Fig. 2 a longitudinal section, of a form or last for receiving or to enter a boot or shoe, provided 20 with my invention, the lining being represented in this figure in dotted lines as applied to the points, holders, or catches. Fig. 3 is a longitudinal section of a form or last provided with my invention, with a shoe applied 25 thereto and to the lining.

My invention consists in providing the surface of the form or last against which the inner sole of a boot or shoe has heretofore been laid when subjected to the "beating-out" process with catches, holders, or points, there being a spring-point at the toe to catch and hold the sock-lining or cover for the inner sole when applied thereto, so that after 30 said lining, with its outer surface coated with cement, is attached to the said catches or points, and the shoe or boot is applied to the form and pressed into contact with the said lining and onto the form or last for the purpose of shaping the sole and laying the channel, the said lining will at the same time be 35 securely attached to and smoothly laid on the inner sole, and on removal of the shoe or boot from the form or last, owing to the construction of the catches, holders, or points, the said lining or inner-sole cover, firmly adhering to the inner sole of the shoe or boot, will be readily disengaged from the said holders or points and offer no resistance to the removal of the shoe from the form or last.

In the drawings, A denotes the form or last, 50 made to receive or to enter the shoe and give shape to its sole by being pressed into contact therewith, in the heel and ball portion of which are fixed studs a a', provided with conical points. b is a spring catch or holder, its 55 point, tapered as shown, extending toward the toe of the form or last, and its shank c being represented as passing through a hole, d, in the said toe portion and secured to the form or last by a screw, e, all as represented in Fig. 2. 60 The shank of the catch or holder b may be arranged in a groove in and so as to extend a little below the upper surface of the said form or last and secured therein; or one or more catches or points may be fixed in the said toe 65 portion with the points inclined in a direction toward the toe. Either of said arrangements will answer the purpose of holding the said lining or cover at its toe. In applying the 70 said lining or cover to the form or last the toe of it is first secured to the catch or holder b, then the heel and ball portions of it to the studs a a', (see Fig. 2,) the upper surface of the said lining or cover having been first 75 coated with a suitable cement. Next a shoe or boot prepared ready for its sole to be molded or "beat out," as it is termed, is applied to the form and pressed into contact with the said sock-lining or inner-sole cover, and down upon the form. After being subjected to the requisite pressure, by raising 80 the heel of the shoe the said lining or cover will easily free itself from the studs a a', and in completing the removal of the shoe from the form or last the toe of the said lining or 85 cover will be moved away and freed from the catch b.

By my improvement much time is saved in the aggregate in applying sock-linings or inner-sole covers to the inner soles of boots or shoes, as hereinbefore described, over the means previously employed for the purpose, and the said linings or covers can be located in position on the inner sole with greater accuracy, and laid smoothly or with less liability to wrinkle than heretofore.

Having described my improvement, what I claim is—

1. A form or last to enter a boot or shoe provided at its toe with a spring-catch and in its heel and ball portions with catches, holders, or points to support the sock-lining or cover for the inner sole while a boot or shoe is being applied to the form or last, and is pressed or forced into contact with the adhesive surface of the said lining or cover and onto the form to give shape to the sole thereof, the toe-
5 catch having its point inclined forward, all as set forth and represented.
2. In combination with a form or last to enter a boot or shoe, the spring toe catch or
10

holder *b*, having its point inclined forward, and the heel and ball holders or points *a a'*, 15 for supporting a sock-lining or inner-sole cover while being applied and secured to the inner sole of a boot or shoe, substantially as shown and set forth.

In testimony whereof I affix my signature in 20 presence of two witnesses.

AUGUSTUS S. TROWBRIDGE.
